Attorney

UNITED STATES PATENT OFFICE.

JOHN P. SWEDENBORG, OF AKRON, OHIO.

GARMENT STRETCHER.

Application filed May 31, 1921. Serial No. 473,633.

To all whom it may concern:

Be it known that I, JOHN P. SWEDENBORG, a citizen of the United States, residing at Akron, in the county of Summit and State 5 of Ohio, have invented new and useful Garment Stretchers, of which the following is a specification.

This invention relates to garment stretchers, and more particularly to a device especially designed for stretching trousers or the like, it being the primary object of the invention to provide a device of this character which may be adjusted to adapt the same for use with trousers of various sizes and 15 shapes.

A further object of the invention is to provide a pair of trouser engaging arms, there being provided a connecting means for connecting the arms, the connecting means 20 being in the form of a hook.

A still further object of the invention is to construct the connecting means of resilient material, so that the same will normally exert a lateral pressure on the trouser engaging 25 arms of the device.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention. 35

Referring to the drawing:—

Figure 1 is a front elevational view of a garment stretcher constructed in accordance with the present invention.

Figure 2 is a sectional view taken on line 2—2 of Figure 1.

Figure 3 is a sectional view taken on line 3—3 of Figure 1.

Figure 4 is a sectional view taken on line 4—4 of Figure 1.

Referring to the drawing in detail, the device comprises a pair of opposed arms, each arm including an upper section 5 and 50 a lower section 6, the upper section being provided with enlargements 7 at the upper end thereof, and enlargements 8 at the lower ends thereof, the enlargements 7 being pro-

vided with a plurality of openings to accommodate the bolts 9, which bolts secure 55 the connecting member 10 to the arms.

This connecting member is formed of a length of wire bent to provide a hook member 11 and a pair of resilient leg members 12 which have loops 13 formed at the ends thereof, the loops being designed to accommodate the bolts 9. Secured to the opposed arms of the device is a locking member which includes a plate 14, which is apertured to receive the bolt 9 to which is secured a link member 15 that connects the chain 16 to the plate 14, there being provided a hook member 17 secured to the opposite arm of the device and adapted to accommodate a link of the chain 16 to hold 70 the arms in a predetermined position with respect to each other.

Having connection with each of the upper sections 5 of the respective leg members, is a resilient arm 18 that has its free end overlying a portion of the opposite section of the arm associated therewith, which section is provided with an opening to receive the pin 19 which is carried by the arm 18. Thus it will be seen that as the sections 6 are moved upwardly into engagement with the ends of the sections 5, the sections 5 and 6 are securely held together. It might be further stated that in order to secure the sections 6 against lateral movement, bars 6' are secured to the sections 5 and extend beyond the lower ends of the sections 5 to provide guideways. The ends of the sections 5 and 6 of each arm are formed with shoulders as clearly illustrated by Figure 1 of the drawings, so that when the sections are moved into engagement with each other, movement of one section with respect to its adjacent section is prevented.

In the use of the device, the chain member 16 is positioned over the hook 17 to draw the arms of the device into parallel relation with each other, whereupon the device is positioned within the trouser leg, it being understood that the arms should be positioned in a manner so that one arm will lie within the crease of the front portion of a leg, while the opposite arm lies within the crease in the rear of the leg. With the arms in these positions, the chain is removed from the hook 17, with the result that the legs 12

move the arms laterally to the end that the lateral pressure causes the arm to form creases in the trousers.

What is claimed as new is:—

5. A garment stretcher comprising opposed arms, each of the arms comprising a pair of sections, bars secured to opposite sides of one section of each arm to provide guideways, the opposed section of each arm having a portion thereof disposed between the bars and having an opening, a spring arm

carried by one section of each arm, and carrying a pin, said pins adapted to move into the openings of opposed sections to secure the sections together.

15

In testimony that I claim the foregoing as my own, I have hereto affixed my signature in the presence of two witnesses.

JOHN P. SWEDENBORG.
